UNITED STATES PATENT OFFICE

ALBERT F. BEMIS, OF NEWTON, MASSACHUSETTS, ASSIGNOR TO BEMIS INDUSTRIES, INC., OF BOSTON, MASSACHUSETTS, A CORPORATION OF DELAWARE

BUILDING

Application filed December 2, 1925. Serial No. 72,678.

This invention relates to a method of building construction characterized more particularly by the use of standardized units which may be preformed and then assembled in situ. Units of the type disclosed in this application may be produced of a wide variety of materials in accordance with individual requirements and with the different local sources of supply in different vicinities. 10 They may readily, for example, be made of light material permitting ease of handling and the construction of a building with a minimum amount of labor and with little need for hoists, derricks, and the like, while 15 buildings constructed in accordance with this invention may also be made of fireproof or semi-fireproof materials, when desired. The units are adapted to provide insulating air pockets between the inner and outer faces 20 of walls or partitions and to permit the filling of certain parts of the walls with cementitious material, such as concrete, or the interposition of structural parts therein to suit any requirement. When constructed of suitable material with concrete poured therein, 25 the units may be combined to form foundations or similar structures, while furthermore these units are adapted to constitute forms for the pouring of concrete columns, girts or 30 the like, thus dispensing with practically all necessity for the erection of temporary wooden forms during the construction of a building having a concrete framework. This type of construction is also readily adaptable 35 to combinations with different types of reinforcing means such as metal bars or rods.

In one aspect this invention consists of the provision of formative units which may constitute the basic outline for the walls of a 40 building, such as the side walls, partitions, foundations, floors or flat or inclined roofs. Usually these formative units will be light forms designed to outline walls and not to afford structural support, but in certain 45 cases they may be incorporated in an assembly to form a structural component of a building or the like, thus performing a function commonly associated with the framework.

Another aspect of this invention concerns 50 the aligning and spacing of these units and

their attachment to the surrounding structural framework, certain phases of such an arrangement being an improvement upon the disclosure in my copending application Serial No. 33,173, filed September 12, 1925. A 55 further aspect of this invention includes the application of outer covering means which may be readily combined with the formative units to form wall structures having suitably disposed frame members. 60

Formative units may be produced of a wide variety of materials such as metal, wood or other fibrous materials such as paper or similar compositions, cementitious material such as gypsum or Portland cement, fibrous, 65 discrete or granular materials combined with cementitious material, such as straw-board, chip-board, or such as the combination of sand, cinders, etc., with cementitious material, or other combinations of these and 70 other suitable materials. The covering means for the units may be likewise produced of a wide variety of materials such as metal, wood, fibrous materials of all sorts, cementitious material such as stucco or gypsum, or 75 they may be made of clay, or straw-board, chip-board or celotex, or they may be light concrete slabs formed of a combination of any suitable materials. These units are preferably preformed and are of standardized 80 sizes, the formative units usually being of a length corresponding to some dimension of a room or building such as the height of a story, but if desired they may be cut to suit individual installations. 85

Many other objects and advantages of this invention will also be apparent to those skilled in the art upon a reading of the specification in conjunction with the accompanying drawings. 90

In the drawings:

Fig. 1 is a horizontal section through portions of adjoining walls of a building;

Fig. 2 is a detail perspective;

Fig. 3 is a detail section;

Fig. 4 is a perspective view of one form of wall construction;

Fig. 5 is a similar view of a slightly different construction;

Fig. 6 is a diagrammatic side elevation; 100

Fig. 7 is a horizontal section of a modified form of wall;

Fig. 8 is a view similar to Fig. 2 of another embodiment of the invention;

Fig. 9 is a detail perspective of the top of a wall assembly;

Fig. 10 is a view similar to Fig. 1 of a different form of the invention;

Fig. 11 is a section through portions of a side wall and floor;

Fig. 12 is a broken perspective view of a wall assembly with parts removed;

Figs. 13 and 14 are perspective views of details of construction;

Fig. 15 is a detail perspective view similar to Fig. 9 showing another form of my invention;

Fig. 16 is a detail sectional view;

Fig. 17 is a detail view of a wall assembly;

Fig. 18 is a vertical section of a wall construction;

Fig. 19 is an enlarged section on line 19—19 of Fig. 18;

Fig. 20 is a vertical section of an optional wall construction;

Fig. 21 is a horizontal section of a modified wall assembly;

Fig. 22 is an enlarged section on line 22—22 of Fig. 21;

Fig. 23 is a view similar to Fig. 11 of another type of construction;

Figs. 24 and 25 are vertical sections of floor constructions; and

Fig. 26 is a view of an optional wall construction.

In accordance with the preferred embodiment of my invention a strip 4, having cylindrical projections 3 formed thereupon in closely juxtaposed position is inset in, or secured upon the upper surface of a foundation 2 of a building. To form a wall upon the foundation 2 upright I-beams 5, or other members preferably suitable for reinforcing concrete columns, are located at the ends of the proposed wall or at its intersections with other walls. Brackets 7 are secured to the tops of the uprights 5 and are adapted to support temporarily a ranger 8 having juxtaposed frusto-conical members 9 thereupon which correspond to the members 3 inset in the upper surface of the foundation, but may have a greater depth. The members 8 and 9 may be made of any suitable material, but preferably of some light substance, such as paper-board, thin sheet metal or the like. Hollow tubular units 1 made of any suitable substance but preferably of a light composition, such as paper-board, straw-board, chip-board, or the like, have their lower ends slipped over the juxtaposed cylindrical portions 3 projecting from the foundation 2. The members 3 may be of such a size that they permit the tubular units 1 to rest upon the strip 4 but prevent them from any substantial movement in a horizontal direction.

The members 1 are therefore assembled upon the foundation in approximate alignment with a truncated member 9 projecting slightly into each of their ends. Brackets 7 which are temporarily attached to the upright metal beams 5 are then removed thus permitting the dropping of the ranger 8 upon the upper ends of the units 1 with the tapered walls of conical portions 9, which engage the interiors of the tubular members, guiding them into accurate alignment as the ranger 8 is brought downwardly upon the tops of the units. The ranger 8 may form a covering means for the tops of the units 1 and, if desired, have holes 10 therein at intervals to permit the pouring of concrete into certain units to form spaced concrete columns in the structural walls.

Obviously there are many similar optional means of combining the units, for example temporary wooden struts may be used in place of the I-beams 5 or the like, or suitable uprights may be located at each end of the wall and be connected by a horizontal member which may or may not ultimately form a reinforcement for a concrete girt along the top of the wall. For example pipes, such as disclosed in my copending application No. 36,852, filed June 13, 1925, may be located in this manner, having the strip 8 temporarily suspended from the horizontal connecting member or from the uprights as by ropes, hooks or brackets. In the case of long walls, uprights 5 may be disposed at suitable intervals therealong rather than only at corners or intersections with partitions or the like.

This system of spacing and aligning the units obviously may be used for all sorts of walls such as inclined roofs, flat roofs, floors and the like.

In certain installations it may be found desirable to lift the ranger directly into its assembled position, while in other installations conical projections, truncated or otherwise, may be substituted for the lower projections 3.

Members 1 and their aligning means as so assembled are preferably intended to be primary formative means for the construction of walls and are ordinarily not designed to take the place of the structural framework such as is common in building construction, although in certain cases the units may constitute a solid construction, suitably reinforced by concrete poured into or between the units, to form a strong structural component of a building.

To provide an outside finishing surface or a surface suitable for the application of finishing material, I may provide the wall with courses of slabs 15. These slabs may be of a wide variety of materials such as wood, gypsum, paper composition, clay tiling or similar substances which are adaptable for this purpose.

The slabs 15 preferably are applied to the opposite sides of the structural wall, formed by the units 1, and may be held in place by the connecting plates 26 shown more particularly in Fig. 2, which may be of any suitable material, such as wood or any of the materials previously referred to. These plates 26 are preferably interposed between courses of slabs 15 and may have means 27, such as ribs 10 or the like, projecting into the margins of adjoining courses of blocks. Instead of ribs 27, nails 29 or the like can be used in conjunction with ribs as shown in Fig. 3, or the slabs may be rabbeted and the plates 15 nailed thereto as shown in Fig. 20. The mid-portions of the plates 26 have semi-circular recesses 28 to engage the sides of units 1 between which they extend and they preferably have a width less than the distance 20 between the outer surfaces of the slabs 15, thus providing recesses between the slabs for the pointing of mortar or the like, thereby permitting the construction of an outer surface resembling a stone wall. Between the ends of the slabs 15 suitable filler strips 31 may be interposed to provide similar recesses. If desired, the ends of slabs 15 may be grooved to engage ribs on strips 31 or on vertical connecting plates 26^a (Figs. 16 29 and 17), the ends of which form means for the pointing of mortar and the body portions of which extend between adjoining units 1.

In certain cases it may be desirable to dispose 35 standardized metal members 71, or the like, vertically between plates 26, (Figs. 18 and 19) thereby accurately locating the latter between courses of slabs and also constituting means for providing recesses at the ends of the slabs 15 for the interposition of mortar. Members 71 preferably extend between mid-portions of plates 26 and are in substantially 40 abutting relation with the inner surfaces of slabs 15. Their ends may be secured to the plates in any desired manner and, as shown, have the flange portions 72 secured by bolts 73 to plates 26.

In some instances one or both edges of the plates 26 may have prongs 35 formed thereon to project beyond the wall surfaces and to be bent over as shown in Fig. 8, providing additional means for the attachment of finishing materials such as plaster or stucco 37. Such an arrangement is advantageous with 55 plates and slabs of fiber board or similar material.

In constructing a building, I prefer to omit tubular units 1 at the corners but have the extensions of blocks 15 constitute a form together with the units 1 at the ends of the walls, thus permitting the pouring of cementitious material, such as concrete, around the I-beam, and thereby forming a reinforced concrete column at the corners of the building 60 (Fig. 1). At these corner spaces between

courses of blocks 15 may be filled by L-shaped brackets 29 serving to secure the blocks in place, and when necessary additional reinforcing means may be applied.

The outer layer of slabs 15 may be extended upwardly to constitute a form for the outside of a cement girt 19 in a similar manner. Plates 26 may be omitted adjoining the girt course of slabs, for example the overlapping edges of rangers 8 may be secured to the slabs and provide recesses for the interposition of mortar. Any temporary means may be used to hold the tops of the girt slabs 15 in place while the girt 19 is being formed. The concrete for the girt and the vertical columns may be poured in one operation, thus forming a monolithic structure, if desired, while the girt member may be combined in a wide variety of ways with different floor constructions, such as suggested in my copending application Serial No. 72,675 filed on even date herewith and now issued as Patent 1,715,587. The depth of the girt and the floor may substantially correspond to the height of the adjoining slabs 15 in this type of construction.

If it is desired to add another story above girt 19, a ribbed plate 34 is disposed thereupon with the cylindrical projections 3. This plate may be secured to the margins of slabs 15 in a manner similar to that of the plate 8 previously described.

Whenever it is desired to fit door or window frames into the wall, this construction readily permits the fitting of bucks 32 between the slabs 15 to define the opening for such a frame, as shown in Fig. 1.

A desirable optional arrangement is shown in Figures 21 and 22, wherein the spacing members 92 are disposed between each of the tubular units 1 and have the projections 93 at their ends engaging plates 26. By the use of these spacing members 92 the structural wall may be divided longitudinally into two parts, either of which may be filled with cementitious material 94, if desired, or left unfilled to provide an insulating space, while in certain cases portions of the plates 26 may be broken away, or holes made therein, to permit the location of the heating pipes or the circulation of air through these portions of the structural wall. With such arrangements it may be desirable to form openings in the slabs 15 upon the inner side of the wall to permit the circulation of air for heating or ventilation.

In other cases, however, tubular units 1 may be used for heating or ventilating purposes, heating units may be disposed therein or the members themselves may be used as ducts for heated or unheated air, apertures being formed in the slabs 15, or certain of these slabs being pivotally mounted, to permit air circulation about the units and into the rooms.

Instead of connecting slabs 15 by plates 26, I may use staples 16, shown more particularly

125

130

in Figs. 10, 13 and 14, which may be of many different forms. As shown each staple 16 has a shank portion 17 adapted to extend between the units 1 and has portions 18 disposed at right angles to its ends which are 5 adapted to project into the marginal portions of rows of courses of slabs. In the case of the slabs of wood or fibrous material the ends of portions 18 are preferably pointed and 10 forced in the slabs, while in the case of tiles or cementitious materials the projections may be blunt and holes may be made at intervals in the margins of the slabs to engage therewith. Staples 16 are more particularly designed to 15 engage between courses of slabs 15 although they may be also located between the ends thereof.

As shown in Fig. 26, slabs 75 may be provided in a similar type of construction, being 20 recessed at 76 to engage around a substantial portion of the units but leaving a narrow space 77 between the inner and outer slabs suitable for insulation or the interposition of cementitious material 78. As in the case of 25 the slabs previously described, any suitable fastening means may be used for slabs 75, such as the tie staples 16, as shown. With this type of construction the units 1 may be made of a very light material, such as paper, and, 30 if desired, certain of these units may be filled with concrete or the like, to strengthen the wall structure. This construction is suitable for foundations as well as walls, floors, and roofs.

Obviously these forms of construction may be adapted to many other installations and 35 different embodiments; for example, inclined walls such as those forming the surfaces of pitched roofs or horizontal walls such as 40 those constituting floors or flat roofs may be constructed according to the principles described above. The slabs 15 may form the interior finish upon the walls or ceilings or provide a surface for roofing material, flooring or the like. The principles of this invention 45 may be combined with many conventional modes of construction well known in the art, or with building constructions or units such as disclosed in my application No. 50 33,173, filed September 12, 1925, or in my applications Nos. 72,673 and 72,674, filed on even date herewith now matured into Patents Nos. 1,671,462 and 1,693,742, respectively. The essential principles of this invention may be 55 varied to suit individual conditions and the preferences of particular builders, for example, as shown in Fig. 14, the blocks 15 may be recessed to permit the interposition of mortar or similar material. In such an embodiment of my invention (Fig. 14), the ends of 60 the blocks are preferably bevelled to provide recesses 39, the staples 16 having their ends 18 projecting into the recessed portion of the blocks and affording advantageous means 65 for pointing the mortar 21.

Rather than having continuous rangers 8 provided with frusto-cones 9, if desired, the cones may be of conventional form with an apex, certain cones being truncated to permit the pouring of cementitious material in certain tubular units 1. More particularly in cases of heavy construction when the units 1 may be of wrought iron or the like, it may be found desirable to provide a ranger 48 (Fig. 15) with openings 49 adapted to receive truncated conical members 50, which may be disposed therein individually as each unit 1 has its upper end brought into place.

Instead of having conical members 9, it 70 may be desirable to provide elongate key members 36 (Fig. 14) such as described in my copending application Serial No. 72,674, filed on even date herewith now matured into Patent 1,693,742, but to taper the key members and engaging slots to permit a rapid 75 assembly of the parts.

In another way of aligning the units which 80 may be used adjoining a girt member or in any analogous position, aligning members 86, which may be tubular, are provided with the shoulders 87 to engage the upper ends of the lower units and the lower ends of the upper units and also have portions 88 projecting into these parts of the units to form aligning 85 means for the same. With such an arrangement a girt 19 may be formed about the tubular aligning members 86, which telescope with the wall units.

In certain cases it may be desirable to apply slabs 40 to tubular units in various other ways, for instance as by nailing them, or as 100 disclosed in Figs. 4, 5 and 7. For example units 42 may have four radial flanges 43 thereon, pairs of which are joined to the similar members upon adjacent units at either 105 side by strips 46, the other pairs of which engage the edges of elongate vertically arranged blocks or slabs 40 with flash strips 44 covering the joints.

Fig. 5 illustrates a somewhat similar construction, wherein the units 65 may be formed of fiber-board, or the like bound by an inner layer 69 of cementitious material such as gypsum or the like. Adjoining flanges 67 of 110 these members may be clamped together by strips 66 of resilient metal which are resiliently engaged with the flanges. Slabs 61 may be held in place by the T-shaped strips 62 which have wedge-shaped portions 63 driven between the laminations of flanges 67 of units 65, thereby forcing these flanges into 115 gripping relation with the edges of slabs 61, disposed between flanges 67 of adjoining units, in the manner described with reference to Fig. 4.

Elongate slabs 55 (Fig. 7) may be joined in 120 pairs by connecting rods 52 pivotally or otherwise secured to their mid-portions. A wall may then be assembled by erecting a unit 1, placing slabs 55 at either side thereof with 125 130

the rod 52 at one side of the unit, then apply another unit 1 at the opposite side of rod 52, and so on, assembling units and pairs of slabs alternately with rods 52 extending between the units.

5 Floor constructions may also be provided having an arrangement of parts somewhat resembling that illustrated in Fig. 4, for example floor units 81 may be provided with the flanges or nubs 82, (Fig. 24) which extend between ceiling planks 83, or the like, at the lower portions of the units, and which at either side of each of the units are in substantially abutting relation with similar nubs upon adjoining units. Disposed upon the upper portion of plank 83 is a metal fastening member 84 which may be of T-section, with a portion 85 inserted between adjoining nubs 82 and with portions of its upper margin bent over in opposite directions to hold the plank 83 in place and to engage with concrete 86 poured between the units 81, if desired. A somewhat similar arrangement is illustrated in Fig. 25, wherein the planks 83 are provided with upwardly disposed fastening members 89 of wood, or the like, and the spikes 90 are driven through the nubs of adjoining units 81 with their ends projecting into member 89 and with their heads engaged by the concrete 86. With constructions of the type illustrated in Figures 24 and 25, any conventional ceiling finish may be applied to the planks 83, when desired, while flooring may be secured directly upon the upwardly disposed nubs of units 81 or a layer of concrete may cover the same.

I claim:

1. In a building construction a structural wall or the like, formed about a series of closely spaced columnar units and having a series of slabs disposed upon opposite sides of the units with connecting members secured to the marginal portions of slabs upon opposite sides of the units and extending into the spaces between the units.

2. In a building construction a structural wall or the like, formed about a series of closely spaced columnar units and having a series of slabs disposed adjacent one side of the units with connecting means between the edges of adjacent slabs tying them into a continuous layer defining a surface for the structural wall, said connecting means also securing the slabs to the units.

3. In a building construction a structural wall or the like, having two layers of slabs at its opposite sides, which define the structural wall, and having plates connecting the ends of pairs of slabs in one layer with pairs of slabs in the other layer, said plates including body portions extending between adjoining slabs and having means at its ends interfitting with the marginal portions of the same.

35 4. In a building construction a structural

wall, or the like, formed about juxtaposed columnar units and having a layer of slabs at either side of the units, and plates connecting slabs in one layer with the other layer, each plate having a body portion recessed to engage columnar units and its ends secured to slabs in the opposite layers.

5. In a building construction a structural wall or the like, having two layers of slabs defining the opposite faces of the wall, connecting plates extending between the layers of slabs and having ends extending between adjoining slabs for a portion of their width to provide grooves therebetween for the interposition of mortar.

6. In a building construction a structural wall or the like formed about juxtaposed columnar units and having a layer of slabs at either side of the units, and plates connecting slabs in one layer with slabs in the other layer, each plate having a body portion recessed to engage the columnar units and having ends extending between adjoining courses of slabs.

7. In a building construction intersecting structural walls formed about a series of closely spaced columnar units, slabs disposed upon opposite sides of the units, said slabs being extended to cooperate with adjoining units to enclose a space at the intersection of the walls to provide a form for a concrete frame member.

8. In a building construction intersecting structural walls or the like formed about series of closely spaced columnar units, slabs disposed upon opposite sides of the units, said slabs being extended to cooperate with adjoining units to enclose a space at the intersection of the walls to provide a form for a concrete frame member and a metal member disposed within said space to provide a reinforcement for the same.

9. In a building construction a structural wall formed about a series of closely spaced columnar units with ends engaged with frusto-conical means projecting from an adjacent frame member, and a series of slabs disposed upon opposite sides of the units to define the outer faces of the structural wall or the like.

10. In a building construction including a frame member and a series of closely spaced columnar units, frusto-conical elements projecting from an adjacent frame member into ends of the tubular units thereby holding the units in alignment and tying them to the structural framework.

11. In a building construction, including a frame member and a series of juxtaposed columnar units, tapered means projecting from an adjacent frame member into the tubular units to hold them in alignment.

12. In a building construction including a frame member and a series of closely spaced columnar units, tapered means pro-

jecting from the frame member to hold the units in spaced position.

13. A method of building construction characterized by the assembly of juxtaposed columnar units and comprising the provision of aligning means upon a base, the engaging of the lower ends of columnar units with the aligning means to bring them into substantial alignment, disposing tapered aligning means adjacent the other ends of the units, moving one of the aligning means towards the other, thereby guiding the units into accurate alignment.

14. A method of building construction characterized by the assembly of juxtaposed columnar units and comprising the provision of aligning means upon a base, engaging the ends of a series of columnar units with the aligning means, thereby bringing them into substantial alignment and spaced position, suspending tapered aligning and spacing means from upright members, said last named means being disposed above the upper ends of the columnar units, disconnecting the last named aligning and spacing means from the upright members to permit the tapered aligning means to be brought into close engaging relation with the upper ends of the units with the assistance of gravity, thereby drawing the units into accurate alignment, placing blocks at the sides of the units with portions of said blocks extending beyond said units to provide a form for the pouring of concrete frame members with reinforcing means therein formed by the aforesaid upright members, thereby forming a wall with reinforced concrete frame members.

15. In a building construction a structural wall or the like, formed about a series of closely spaced columnar units with a layer of blocks at either side, means extending from one layer of blocks to the other between the units and having portions projecting part way between adjoining courses of blocks to permit the pointing of mortar disposed between the blocks.

16. A building construction comprising adjoining wall portions meeting at a corner, a row of closely spaced columnar units in each of the wall sections, layers of slabs disposed upon the opposite sides of the rows of units, the slabs being extended to enclose the space at the corner and the rows of units terminating adjoining the corner, whereby the slabs and the end unit of each row cooperate in enclosing a space to provide a form for a concrete frame member at the corner of the wall sections.

17. A building construction comprising a wall, a layer of slabs defining one face of the wall, connecting elements in interfitting engagement with edge portions of adjoining courses of slabs, said elements cooperating with the edge portions of the slabs in

providing grooves for the reception of mortar.

Signed by me at Boston, Massachusetts, this 2nd day of November, 1925.
